US0D1072571S

(12) United States Design Patent (10) Patent No.: US D1,072,571 S
(45) Date of Patent: * Apr. 29, 2025

(54) BEVERAGE CONTAINER

(71) Applicants: Teresa Schweikart, Vero Beach, FL (US); James Schweikart, Vero Beach, FL (US)

(72) Inventors: Teresa Schweikart, Vero Beach, FL (US); James Schweikart, Vero Beach, FL (US)

() Term: 15 Years

(21) Appl. No.: 29/891,575

(22) Filed: May 8, 2023

(51) LOC (15) Cl. 07-01

(52) U.S. Cl.

USPC D7/515; D7/510; D21/731

CLAIM

The ornamental design for the beverage container as shown and described.

DESCRIPTION

FIG. 1 is a front view of the beverage container of the present invention; and

FIG. 2 is a rear view of the present invention; and

FIG. 3 is a left side view of the present invention; and

FIG. 4 is a right side view of the present invention; and

FIG. 5 is a bottom view of the present invention; and

FIG. 6 is a top view of the present invention; and

FIG. 7 is a perspective view of the present invention; and,

FIG. 8 is a perspective view of the present invention with the cap removed.

1 Claim, 5 Drawing Sheets
